UNITED STATES PATENT OFFICE

164,839

LADY'S STOCKING

John C. Bergner, Lansdowne, Pa.

Application July 12, 1950, Serial No. 11,096

Term of patent 14 years

(Cl. D47—7)

To all whom it may concern:

Be it known that I, John C. Bergner, a citizen of the United States of America, residing at Lansdowne, in the county of Delaware and State of Pennsylvania, have invented a new, original, and ornamental Design for a Lady's Stocking, of which the following is a specification, reference being had to the accompanying drawing, forming a part hereof.

The drawing is a perspective view of a lady's stocking, showing my new design.

My design comprises a series of diamonds and triangles formed of heavier or reinforcing yarn arranged in triangular formation on the heel portion of a stocking as shown.

I claim:

The ornamental design for a lady's stocking, as shown and described.

JOHN C. BERGNER.
